United States Patent Office.

NICHOLAS H. SIRRELLE, OF BALTIMORE, MARYLAND, ASSIGNOR
TO MARTIN BURNELL AND WILLIAM TASSIL TASSIL.

Letters Patent No. 92,112, dated June 29, 1869.

IMPROVED BOTTLE-WASHING MACHINE.

The Schedule referred to in these Letters Patent and making part of the same.

To all whom it may concern:

Be it known that I, NICHOLAS H. SIRRELLE, of Baltimore, in the county of Baltimore, and State of Maryland, have invented certain new and useful Improvements in Bottle-Washing Machines; and I do hereby declare the following is a full and exact description thereof, reference being had to the accompanying drawings, making part of this specification.

My invention consists—

First, of a hollow mandrel, connecting at one end with a water-pipe, while the other end is provided with an injection-pipe and brush, over which the mouth of the bottle is passed, the water being discharged into the bottle, which is speedily and effectually cleansed by the action of the brush revolving therein.

Second, in the arrangement on the injection-pipe, of a thimble or sliding valve and a spiral spring, in such a manner that the valve will be slid back, so as to uncover the escape-orifices, by pressing against it with the mouth of the bottle, and be returned to its normal position, by the action of the spring, when the bottle is withdrawn, thereby again shutting off the escape of the liquid.

In the drawings above referred to—

Figure I is a vertical transverse section of my improved machine, in line of the mandrel.

Figure II is a similar section through the rinsing-box.

Figure III is a plan.

Like letters of reference designate like parts in each of the figures.

A A is the frame of the machine, of any suitable construction, for supporting the parts.

B is a rectangular tub or sink, elevated at a convenient height for receiving the waste water from the washing and rinsing-apparatus.

C is a hollow mandrel, to which motion may conveniently be imparted by means of a belt, D, connecting a pulley, f, on the mandrel with a driving-wheel, G, on a crank-shaft, H, operated by a treadle, I, and connecting-rod j.

Other power and driving-mechanism, however, may be employed, if preferred.

The rear end of the mandrel is provided with a stuffing-box and gland, k, which receives the end of a stationary pipe, L, to which attaches the hose m or other pipe, provided with a stop-cock, and connecting with a hydrant, or reservoir containing the washing-liquid, elevated a few feet above the mandrel, to form a sufficient head to force the water through the mandrel.

To the other end of the mandrel attaches, in any

suitable manner, a nozzle or injection-pipe, N, of different sizes, in the end of which is inserted the cleaning-brushes o, constructed of hair, or other suitable material.

The end of the nozzle-pipe is formed with a number of jet-orifices, s s, over which fits, so as to slide, a thimble, p, provided with a flange, q.

Back of this thimble, and surrounding the pipe N, is a spiral spring, t, which presses against the former, and causes it to cover the jets, except when overcome by the pressure of the bottle x, as will presently be explained.

The rinsing-device, before alluded to, consists of a series of vertical jets, r; supplied with water by means of a main pipe, u, and suitable branches u' u', from which they extend upward.

Over these jets is arranged a board, V, perforated to correspond with and receive the jets.

W is a box or case, resting on the board V, and divided into cells w, up through the bottom of each of which opens or extends one of the jets r, as clearly shown in Figs. II and III.

The operation of my improvements, thus constructed, is as follows:

The bottle to be washed is passed over the brush o, the mouth pressing against the flange q of the valve, which slides it back, so as to uncover the jets, and permit the water which flows through the mandrel to escape into the bottle. This, in connection with the action of the rotating brush, cleans the vessel in the shortest period of time, which is then placed inverted in one of the cells in the box W, with its mouth over the jet.

When this box or case is filled, water is let on by turning a stop-cock, when the jets, playing upward into the bottles, thoroughly rinse the same, when the case is removed, and an empty one substituted, while the bottles in the former are left to dry.

What I claim as my invention, and desire to secure by Letters Patent, is—

1. The combination of the hollow mandrel C, stationary pipe L, nozzle N, and brush o, arranged and operating as set forth.

2. The arrangement of the thimble-valve p and spiral spring t, substantially as and for the purpose described.

3. The apparatus as a whole, constructed and arranged as described.

N. H. SIRRELLE.
